UNITED STATES PATENT OFFICE.

STEPHEN SUHAJDA AND KAROL ADAMOWSKI, OF OAKDALE, PENNSYLVANIA, AND THEODORE JOHN ADAMOWSKI AND JOSEPH WALTER KUREY, OF WEIRTON, WEST VIRGINIA.

RAIL TIE AND FASTENER.

1,370,163.

Specification of Letters Patent.

Patented Mar. 1, 1921.

Application filed July 3, 1920. Serial No. 393,895.

To all whom it may concern:

Be it known that we, STEPHEN SUHAJDA and KAROL ADAMOWSKI, citizens of the United States of America, residing at Oakdale, county of Allegheny, and State of Pennsylvania, and THEODORE JOHN ADAMOWSKI and JOSEPH WALTER KUREY, also citizens of the United States of America, residing at Weirton, county of Hancock, and State of West Virginia, have invented a new and useful Improvement in Rail Ties and Fasteners, of which the following is a full, clear, and exact description.

The present invention relates broadly to track construction and more particularly to a combined rail tie and fastener.

The principal object of the present invention is to provide a tie having crossed recesses in the upper face thereof for the reception of a rail and clamping means respectively, with improved means for holding the clamping means in position.

A further object of the present invention is to provide clamping means which may be adjusted from time to time as desired, to take up wear and prevent creeping of the rails under tractive influences.

A still further object of the present invention is to simplify rail fastening devices as heretofore constructed by minimizing the number of loose parts required.

The foregoing and other objects, together with their attendant advantages, will be apparent as the invention becomes better understood, by reference to the accompanying specification and drawings forming a part thereof, it being premised that changes may be made in the various details and the manner of operation, within the scope of the appended claims, without departing from the spirit of the invention.

Figure 1 is a plan view partly broken away of a rail tie constructed in accordance with the present invention, with a rail secured in position in one end thereof;

Fig. 2 is a perspective view of one end of a tie having a rail in position therein;

Fig. 3 is a sectional view on the line III—III of Fig. 1;

Fig. 4 is a longitudinal sectional view through a portion of one end of a tie having a rail in position thereon;

Fig. 5 is a sectional view on the line V—V of Fig. 1;

Fig. 6 is a sectional view on the line 55 VI—VI of Fig. 1; and

Fig. 7 is a detail view of a slightly modified form of our invention.

We are aware that it has heretofore been proposed to construct ties having crossed recesses in the upper face thereof for the reception of clamping members, which clamping members have in turn been held in position by rectangular blocks engaging the same. By means of the present invention 65 the use of blocks is eliminated and the number of loose or movable parts thereby correspondingly decreased.

Referring more particularly to the drawings, there is illustrated a tie 2 of any desired material and construction, having transversely extending recesses 3 adjacent the opposite ends thereof for the reception of the base flanges of rails 4 of any usual or well known construction. These recesses are 75 preferably of a depth substantially equal to the height of the base flanges of the rails, so that at the point of union between the rails and the ties an even surface is presented. Extending longitudinally of the tie 80 and crossing the recesses 3 are supplemental recesses 5 having their side walls undercut as shown. At the end of each of the recesses 5 is a vertical opening 6 for the reception of a bolt 7. The width of each of the 85 recesses 3 is preferably slightly greater than the length of each of the undercut recesses 5, whereby clamping members may be readily inserted in position. In the preferred embodiment of our invention we utilize 90 clamping members 8 for the outside of the rail and slightly different clamping members 9 for the inside thereof. The clamping members 8 have a plurality of dove-tail shaped projections 10 formed on the base 95 thereof adapted to engage in turn the upper recess 5 on the outside of the rail and a lower smaller recess 11. The projections 10 are also of less length than the width of the recesses 3, thereby permitting the clamping 100 members to be dropped into position in the recesses 3 and slid longitudinally outwardly so as to extend partially into the vertical openings 6. Where a plurality of dove-tail shaped projections are utilized on the outside clamping members 8, the recesses 3 may 105 each be provided with a central supplemental recess 12 alining with the lower recess 11.

The clamping members 9 for the inside of the rails are preferably narrower than the outside clamping members 8, and are provided with a single projection 13 on the base thereof, for engagement with the inner recesses 5.

In assembling the construction described, the respective clamping members are inserted in position and slid away from the recesses 3 to permit the insertion of the base flanges of the rail. The clamping members are then slid into engagement with the rail, as illustrated, and the bolts 7 screwed into the recesses 6 to lock the clamping members in position. If desired, the ends of the clamping members may be threaded to engage the bolts and provide supplemental locking means therefor.

In other instances, however, it may be desirable to incline the ends 14 of the clamping members, as shown in Fig. 7, and provide the bolts 7' with conical heads 15 for engagement therewith. Due to this construction, it will be apparent that a variable or adjustable clamping action can be exerted on the clamping members by the bolts to take up wear and prevent creeping of the rails.

It will be apparent that if desired we may utilize the same type of clamping members on both the inside and outside of the rails to additionally strengthen the same. In ordinary straight track construction, however, we have found that it is desirable to provide the stronger supporting means on the outside of the rails to prevent spreading thereof.

The advantages of the present invention arise from the construction permitting the ready laying of track without the use of spikes.

Further advantages reside in the form of clamping members and locking means therefor, whereby the number of movable parts is decreased to a minimum.

45 We claim:

1. A rail tie and fastener, comprising a tie having a longitudinally extending recess formed therein and closed at its ends, said recess having undercut walls, clamping members having projections adapted to slidably engage the undercut walls of said recess, and a bolt at each end of said recess in direct engagement in the same horizontal plane with one of said clamping members 50 on one side and one end wall of said recess on the other side to hold the clamping members in position and prevent longitudinal movement thereof, substantially as described.

2. A rail tie and fastener, comprising a tie having at each end thereof transversely and longitudinally extending recesses, the ends of said longitudinally extending re-

cesses being closed and the side walls of said recesses being undercut, clamping members having dove-tail shaped projections 65 formed thereon and adapted to be inserted in said longitudinally extending recesses and adapted to slidably engage said undercut recesses, and locking bolts at the ends of said longitudinally extending recesses, each bolt 70 engaging on diametrically opposite sides thereof and in the same horizontal plane an end wall of one of said longitudinally extending recesses and the end of one of said clamping members for holding the clamping members in position and preventing longitudinal movement thereof, substantially as described.

3. A rail tie and fastener, comprising a tie having formed in its upper face adjacent each end thereof transversely and longitudinally extending recesses, the outer ends of said longitudinally extending recesses being closed and the side walls thereof being undercut, rail-engaging clamps having projections formed thereon for engagement with said undercut recesses, said clamps having inclined outer ends, and locking bolts at the ends of said longitudinally extending recesses, each bolt engaging on diametrically opposite sides thereof and in the same horizontal plane an end wall of one of said longitudinally extending recesses and the inclined end of one of said clamps to hold the same in position and prevent longitudinal movement thereof, said bolts having 95 tapered portions coöoperating with said inclined ends on the clamps to force the same into engagement with the rails, substantially as described.

4. A rail tie and fastener, comprising a tie having formed in its upper face adjacent each end thereof a transversely extending recess for the reception of the base flange of the rail, and a longitudinally extending recess intersecting said first named recess for the reception of clamping members, said longitudinally extending recesses having their ends closed and having undercut walls, there being a supplemental recess with 110 undercut walls extending across each of said transversely extending recesses and throughout a portion of the length of each of said longitudinally extending recesses, and longitudinally movable clamping members 115 slideable in said longitudinally extending recess, substantially as described.

In testimony whereof we have hereunto set our hands.

STEPHEN SUHAJDA.
